UNITED STATES PATENT OFFICE.

GOTTFRIED SCHICK, OF TAMPA, KANSAS.

DESIGN FOR A CLOCK-SHELF.

44,496.

Specification for Design.

Patented Aug. 12, 1913.

Application filed June 4, 1913. Serial No. 771,769. Term of patent 14 years.

To all whom it may concern:

Be it known that I, GOTTFRIED SCHICK, a citizen of the United States, residing at Tampa, in the county of Marion and State of Kansas, have invented a new, original, and ornamental Design for a Clock-Shelf, of which the following is a specification, reference being had to the accompanying drawing, forming part thereof.

Figure 1 is a front elevation, and Fig. 2

is an end view of a clock shelf embodying my design.

I claim:

The ornamental design for a clock shelf, as shown.

GOTTFRIED SCHICK.

Witnesses:

HARRY HUGG,
MARIE STEMMERMAN.
